UNITED STATES PATENT OFFICE.

JOHN E. FUNK, OF STOCKTON, CALIFORNIA.

DITCH-DIGGER.

1,371,752.

Specification of Letters Patent. Patented Mar. 15, 1921.

Application filed November 20, 1919. Serial No. 339,374.

To all whom it may concern:

Be it known that I, JOHN E. FUNK, a citizen of the United States, residing at Stockton, county of San Joaquin, State of California, have invented certain new and useful Improvements in Ditch-Diggers; and I do declare the following to be a full, clear, and exact description of the same, reference being had to the accompanying drawings, and to the characters of reference marked thereon, which form a part of this application.

This invention relates to improvements in ditch digging machines of the type in which the digging is effected by means of an endless driven chain having transverse cutter plates, buckets or other cutting members thereon.

The principal object of this invention is to provide a device adapted to be driven with the chain and secured to the lower sprocket wheel over which the chain passes, by means of which a ditch of any extra width than that normally intended for the machine may be dug.

The device is removable, may be made in different sizes and widths of face to fit the same sprocket wheel, and may be mounted on either or both sides of the same, depending on the width of ditch desired.

I have found this attachment to be of great service, since it permits me to maintain a single ditch digging machine to dig ditches of varying widths. Otherwise it is necessary to have a separate digger for each width of ditch, if such widths vary to any great extent, since the frames etc. of these machines are usually so proportioned and spaced as to be adaptable for only one width of chain digger, or at the most, allowing a variation of only a few inches.

With my attachment however, supposing the original machine to be adapted for digging a ditch 12 inches in width, I am enabled to dig a ditch of 18 or 24 inches width, or of any similar dimensions, depending on the width of face of my attachment.

Another great advantage had with the use of my attachment is that I am enabled to ream out the bottom of a ditch of a given width, or in other words, make it wider for a certain distance from the bottom than it is at the top.

This feature is of especial use for ditches dug for the laying of large sewer, water or other pipe, in which it is necessary to have the ditch adjacent the pipe considerably wider than the pipe in order to be able to place cement, etc., around the same, or to cement the couplings and flanges.

Heretofore to attain this result, it has been necessary to make the entire ditch the same width all the way down, which is a long and costly procedure. With my attachment however, as stated, it is possible to cut the top of the ditch of a width merely sufficient for the lowering of the pipe therein, at the same time reaming out the bottom of the ditch where the pipe is to lay. Or if a ditch is already dug, it may then be reamed out with a separate operation.

Still another sphere of usefulness for the device as a reamer is this:—In certain kinds of land it has been found feasible to have a supply of water flow underground without the need of pipe to inclose the same. With my attachment, operated in conjunction with chain scraper plates of suitable width, a bore of sufficient size for the purpose may be made a suitable distance underground. In the kind of land in which such ditches are feasible, I have found that it is unnecessary to cover the narrow portion at the top, as the dirt from the reamer can be removed with 6 inch scraper plates. This 6" opening at the top gradually comes together, closing over the larger portion at the bottom and leaving a large underground ditch for drainage or sub irrigation.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a side elevation of the rear end of the digging member of a ditch digger, showing my improved reaming and enlarging attachment mounted thereon.

Fig. 2 is a top plan view of the same.

Fig. 3 is a fragmentary cross section

through the chain idler sprocket wheel, showing the method of connecting my device thereto.

Fig. 4 is a cross section showing the shape 5 of a ditch reamed out by my attachment.

Referring now more particularly to the characters of reference on the drawings, the numeral 1 denotes a beam depending downwardly from the rear of the body of the 10 ditch digging machine, this beam being forked at its lower end as at 2, and provided at such end with outwardly projecting split bearings 3.

This beam is pivotally mounted at its upper 5 end, and adapted to be lowered to varying depths, the particular machine on which this beam is mounted being shown and described in my Patent No. 1,073,227 dated September 16th, 1913, though my device is 10 not limited in its adaptation to this particular machine.

Positioned between the forks of the member 1 is a sprocket wheel 4 having long shafts 5 preferably formed integral therewith, journaled in the bearings 3 and projecting therebeyond on both sides. Over the sprocket wheel passes a driven chain 6 having transverse scraper plates or similar digging members 7 projecting outwardly and 30 rigidly secured to alternate links.

This chain is adapted to travel around the sprocket wheel in a clockwise direction with the forward motion of the machine on which it is mounted, and the sprocket wheel, while 35 an idler, necessarily has a positive turning movement in the same direction as the chain, owing to the contact of the sprocket teeth therewith.

My attachment, which I may call a 40 reamer, comprises a hub 8 adapted to be rigidly fixed to the shaft 5 beyond the bearing 3, from which hub radiate a plurality of blades 9. These blades may be of any desired number, but are preferably proportioned apart relative to the pitch of the chain and the spacing of the plates thereon, so that with the common movement of the chain and the blades each of the latter will 45 be in a plane between any two of the chain 50 plates 7.

The blades 9 have a width of face, preferably and approximately half that of the chain plates 7, though this proportion is by no means arbitrary.

55 The radial length of each blade is the same as the radial distance of the outer edge of each chain plate from the center of the wheel 4, and the inner vertical edge of each blade is adjacent the corresponding edge of 60 the chain plates.

The blades are positioned transversely of the hub at an angle of about 45 degrees to the shaft 5 and the sprocket wheel, and converge toward the rear of the latter when in 65 their lowermost position, so that the dirt

will be pushed into the path of the chain plates.

Also, the blades are curved forwardly, as shown at 10 in Fig. 1, in the direction of their rotation, and their outer edges, a short 70 distance from their ends, are cut away for the remainder of their length, as shown at 11, since there is no need of the blade having a side cutting edge for its full length.

In operation, one of these attachments is 75 preferably placed on each end of the shaft 5, one of the same being positioned on the shaft relative to the other so that the blades thereof register between chain plates other than those between which the blades on the 80 other member are alined, and thus feed the dirt to said plates more evenly.

The angular setting of the blades on their hub throws the dirt directly into the path of the chain plates, which must not only 85 raise and carry away the dirt cut thereby, but must also dispose of the dirt cut by the blade attachments on each side.

When it is desired to dig a ditch the full width of the chain plates plus the attachments, the cutting operation may be carried out by stages, since the depth to which the chain may be lowered with each cutting operation must not exceed the diameter of the attachment blades.

When desired to fashion a ditch of the approximate shape shown in Fig. 4, having its upper portion 12 the width of the chain plates and the lower portion 13 the width given by the addition of the reamers, the 100 beam 1 is lowered the full depth of the ditch to be dug, the speed of lowering of course being dependent on the power available to dig the dirt, so that the narrow upper portion and the wider lower portion are both 105 dug at one operation.

When it is desired to use the chain only, without the attachments, the long shaft sprocket wheel is removed, and a short spindle one substituted therefor.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 115 claims.

Having thus described my invention, what I claim as new and useful and desire to secure by Letters Patent is:—

1. In a ditching machine, a sprocket 125 wheel, an endless chain passing over the wheel, and transverse digging members thereon, rotary cutters secured to the sprocket wheel on both sides, said cutters being arranged relative to the sprocket 130

wheel to throw all the dirt dug thereby into the path of the chain plates.

2. In a ditching machine having a sprocket wheel, an endless chain passing thereover, and transverse digging members thereon; radial cutting plates rotatably connected with the sprocket wheel on each side thereof and arranged to throw the dirt into the path of the transverse diggers on the chain, the plates on one side being in staggered arrangement with those on the other, whereby the dirt from each will be thrown into the path of alternate ones of the chain diggers.
- 15 3. In a ditching machine, a sprocket wheel, an endless chain passing over the wheel, and transverse digging members thereon, reamers on both sides of the sprocket wheel, such reamers each comprising a hub adapted to be mounted over the shaft of the sprocket wheel and secured thereto, and radial cutting blades projecting

from the hub, in a transverse plane adjacent the chain blades, the blades being positioned on the wheel in rearward angular relation 25 to the sprocket wheel, when in their lowermost position, whereby the dirt cut by the reamers will be forced into the path of the chain blades with the rotation thereof.

4. In a ditching machine having a sprocket wheel, an endless chain passing thereover, and transverse digging members thereon; reamers on both sides of the sprocket wheel and connected to turn therewith, such reamers each comprising a relatively small hub and radial blades projecting therefrom, the cutting edges of such blades being horizontal and tangential relative to a circle concentric with the sprocket wheel and the blades themselves being positioned in rearward angular relation to said wheel when in their lowermost position.

In testimony whereof I affix my signature.
JOHN E. FUNK.
